FIG.1

FIG.2

FIG.3

FIG. 1 is a plan view of my new gameboard design;

FIG. 2 is a cross-section illustrating the gameboard in platform form with peripheral stand-off support means;

FIG. 3 is a cross-section illustrating the gameboard in planar form.

The characteristic feature of my design resides in a gameboard with a plurality of line-connected circles which are positioned so as to substantially and distinctly outline a hexagon, with each apex area of the hexagon being colored and configured to give the appearance of an inwardly directed arrowhead.

I claim:

The ornamental design for a gameboard, substantially as shown and described.
